FILE CABINET

Herbert Weston, New York, N. Y., assignor to VISI-
Record, Inc., New York, N. Y., a corporation of New York

Application June 15, 1955, Serial No. 36,530

Term of patent 14 years

(Cl. D33—7)

FIG. 1

FIG. 2

Fig. 1 is a front elevation of a cabinet embodying my design; and

Fig. 2 is a perspective view thereof.

The appearance of the back is substantially similar to the front of the cabinet, the principal difference being the absence of the handle on the edge of the cover.

I claim:

The ornamental design for a file cabinet, as shown and described.
